UNITED STATES PATENT OFFICE.

WALTER R. BENJAMIN, OF ST. LOUIS, MISSOURI.

AIR-GUN.

SPECIFICATION forming part of Letters Patent No. 695,025, dated March 11, 1902.

Application filed September 11, 1900. Serial No. 29,674. (No model.)

To all whom it may concern:

Be it known that I, WALTER R. BENJAMIN, a citizen of the United States, residing at St. Louis, in the State of Missouri, have invented 5 a new and useful Pneumatic Rifle, of which the following is a specification.

This invention relates to pneumatic rifles, and has special reference to the type of firearms commonly known as "air-rifles" or "air-guns," and particularly to that class which load at the muzzle and employ shot as projectiles.

The object of the invention is to provide an improved rifle of this character embodying a 15 minimum number of parts, besides such a compact and effective arrangement thereof as to permit of the convenient and rapid charging of the air-reservoir as well as of a quick and effective discharge of the compressed air 20 against the projectile or missile.

To this end the invention contemplates a construction of air-rifle embodying as a part thereof a complete air-pump without detracting in any way from the general appearance 25 of the ordinary rifle. In the accomplishment of this object the invention dispenses with the employment of a separate air-pump, which is adapted to be detached when the air-reservoir is charged, and also dispenses with the 30 use of an air-pump as an auxiliary attachment, such as shown, for instance, in my former patent, No. 627,320. In carrying out this feature of the invention the pump-cylinder has the appearance of being the main barrel 35 of the rifle and being in position and shape like the ordinary barrel of air and similar rifles. Also the said pump-cylinder is utilized to provide at the breech end thereof the air-reservoir, thus permitting of providing the 40 rifle with a comparatively large air-pump and air-reservoir without the addition of extra parts thereto.

A further object of the invention is to provide novel means for dividing or separating 45 the interior of the pump-barrel into a pump-cylinder and an air-reservoir, respectively; and the invention also has in view a novel arrangement of projectile-barrel in connection with compressed-air-conveying means associated with said barrel to provide for securing 50 a most effective discharge of compressed air against the projectile.

Another object is to provide novel means for holding different sizes of projectiles in the same position with reference to the projectile-barrel and the conveyer for transferring compressed air from the air-reservoir to such barrel. 55

With these and many other objects in view, which will more readily appear as the nature 60 of the invention is better understood, the same consists in the novel construction, combination, and arrangement of parts hereinafter more fully described, illustrated, and claimed.

While the essential features of the invention 65 as already pointed out are necessarily susceptible to some modification without departing from the spirit or scope thereof, still the preferred embodiment of the improvements is shown in the accompanying drawings, in which— 70

Figure 1 is a side elevation of a pneumatic or air rifle constructed in accordance with the present invention. Fig. 2 is a longitudinal sectional view thereof, showing the charging-plunger of the pump housed within the pump barrel or cylinder. Fig. 3 is an enlarged longitudinal sectional view of the breech portion of the gun. Fig. 4 is a detail in perspective of the charging-plunger. 80

Like numerals of reference designate corresponding parts in the several figures of the drawings.

In carrying out the invention the usual stock 1 is employed; but in contradistinction 85 to other types of air-rifles, and particularly as an improvement upon the construction of rifle disclosed in my aforesaid former patent, there is directly associated with the stock 1 in the present invention a pump-barrel 2, 90 which while occupying a position and having the shape and size of ordinary forms of barrels at the same time constitutes the cylinder of the charging-pump for the rifle. The said pump barrel or cylinder 2 is preferably constructed of a single piece of tubing, which is of a length equaling the full length of ordinary sizes of rifle-barrels, but which is designed to be made of sufficient diameter or bore to provide a pump-cylinder of maximum 95 size in order that a considerable quantity of air may be readily and quickly stored in the air-reservoir of the pump. The said one-piece pump barrel or cylinder 2 is preferably 100

straight throughout the portion which constitutes the pump-cylinder proper; but the rear portion of said barrel 2 is inclined, as at 3, to constitute the grip portion of the rifle, and this 5 grip portion 3 is fastened directly to one end of the stock 1 by means of screws or equivalent fasteners 4. The said grip portion 3 of the rifle is, as already stated, an integral continuation of the one-piece tubing constituting the pump barrel or cylinder 2, and in addition to constituting the grip of the rifle the said rear inclined portion 3 of the barrel forms within the chamber thereof the air-reservoir 5 for the rifle. This air-reservoir 5 extends throughout the entire grip portion 15 of the rifle or gun, and is consequently of a sufficient size to hold a considerable quantity of air under compression, and by reason of forming a direct continuation of the barrel or cylinder 2 air may be readily charged 20 therein.

In order to provide a separation or division between the pump-cylinder portion of the barrel 2 and the reservoir 5, there is inserted 25 or interposed within the pump-barrel, between these separate parts thereof, a plug 6, which constitutes the bottom or foot valve of the pump-cylinder. The said plug 6 may consist of a cork disk or any other suitable 30 stopper provided therein with an air-port 7, adapted to be covered and uncovered by a check-valve 8, which may be of any approved form, but which for illustrative purposes is shown in the drawings as consisting of an ordinary inwardly-opening check-valve, which 35 opens toward the reservoir 5 to admit air therein and closing over the port 7 under the pressure of the air within said reservoir 5, thereby preventing the escape thereof back 40 through the barrel. In order to insure the firm retention of the plug or foot valve 6 in position within the pump-barrel, the rear sight 9 for the rifle is preferably provided with an inner retaining-stem 10, extending 45 transversely across the pump-barrel in front of the plug 6, thus effectually preventing the same from blowing outward.

The end of the air-rifle opposite the plug 6 is preferably sealed by a suitable stopper 50 11, and in order to complete the construction of pump for charging the said reservoir there is associated with the pump barrel or cylinder a charging-plunger 12. This charging-plunger preferably consists of a straight cylindrical staff loosely registering within the pump-cylinder and substantially filling the same, so that when the plunger is moved entirely within the pump-cylinder the same is 55 completely housed therein, besides forming a filler or guard for the pump-cylinder to prevent projectiles or foreign matter being accidentally placed therein, which might be the case if the plunger were removed therefrom. It will therefore be understood that when the 60 pump is inactive the charging-plunger is housed entirely within the cylinder portion of the pump-barrel 2, as plainly shown in

Fig. 2 of the drawings. The staff of the charging-plunger is provided at its outer end with a finger-grip or knob 13, which is the 70 only part of the plunger exposed when the same is housed within the pump-cylinder, and at its inner end the staff of the plunger has fitted thereto a flexible piston-valve 15 of the type commonly used in connection with 75 air-pump plungers and which on the outward movement of the plunger permits air to pass into the cylinder and on the inward movement of the plunger expands out against the walls of the cylinder and forcibly directs 80 the air through the valved port 7 into the reservoir 5.

Inasmuch as the large pump-barrel 2 forms a rigid framing for the rifle, a minimum size of projectile-barrel 16 may be employed, and 85 in the present invention this smaller projectile-barrel is arranged underneath and longitudinally of the pump-barrel 2 and is rigidly united thereto by solder or other suitable fastening means. The said smaller projectile-barrel 16 extends the full length of the pump-cylinder portion of the main barrel 2, so as to give the appearance of an ordinary magazine-rifle, and said barrel is of the same bore or diameter throughout. The rear end 95 of the barrel 16 has fitted thereto one end of the flexible air-conveyer tube 17, the other end of which tube has a coupling connection 18 with the air-reservoir 5. The rear end of the barrel is flared, so that when the projectile (usually shot) is inserted at the muzzle end of the barrel it rolls back into the flexible air-tube. By this arrangement I have overcome the greatest objection to guns of this type, which objection was that the shot 100 would often lodge so tight that it could not be discharged. It will be observed that by reason of the fact that the breech end of the projectile-barrel is not contracted to hold the shot the full volume of air can enter the projectile-barrel and the gun shoots with greater power. Instead of contracting the projectile-barrel I flare or enlarge its inner end and depend for the holding of the shot on the contraction of the flexible tube due to the 105 mechanism to be presently described. The said flexible air-conveyer tube 17 is arranged at one side of a seat-plate 19, rigidly fitted to the under side of the main barrel, at the grip end thereof, and provided with supporting-ears 20, between which is pivotally hung a releasing-trigger 21, one end of which trigger is adapted to work against a swinging bearing-plate 22, loosely hung at one end, as at 23, in the supporting-ear 24, pendent from 110 one end of the seat-plate 19, and also receiving therethrough the inner end of the projectile-barrel 16. The said flexible conveyer and the parts directly associated therewith, as described, are located inside of the plane 115 of a semicircular or arcuate trigger-guard 25, secured at its ends respectively to the projectile-barrel 16 and the under side of the grip portion 3 of the main barrel 2. The said flexi-

ble conveyer-tube 17 and the trigger device associated therewith are of substantially the same structure and operate in substantially the same manner as the corresponding mechanism disclosed in my former patent; but in the present invention the location of the said trigger mechanism permits of the novel and effective disposition of parts herein pointed out.

10 In using the rifle the releasing-trigger 21 is first set with one end bearing against the plate 22, so as to bind the latter against the intermediate portion of the tube 17, and thereby close the passage-way therethrough, after 15 which the air-reservoir may be charged with air through the medium of the pump described. The projectile to be used is introduced into the muzzle end of the projectile-barrel 16 and passes into the conveyer-tube 17, where it is frictionally held by the flexible walls of said tube. Projectiles of different sizes will be held in the same manner, and when the gun is to be discharged the trigger 21 is pulled upon, which causes the release of 20 the bearing-plate 22 and a consequent opening up of the passage-way through the tube 17, so that the air will forcibly discharge against the projectile or missile and expel the same with force through the projectile-barrel 16.

From the foregoing it is thought that the construction, operation, and many advantages of the herein-described pneumatic or air rifle will be readily apparent to those skilled in the art without further description, and it will be understood that various changes in the form, proportion, and minor details of construction may be resorted to without departing from the principle or sacrificing any 35 of the advantages of this invention.

Having thus described the invention, what is claimed as new, and desired to be secured by Letters Patent, is—

1. In an air-rifle of the muzzle-loading type, 45 the combination with the projectile-barrel, of a pump-barrel having its rear portion extended beyond the rear end of the projectile-barrel and forming an air-reservoir, a valve at an intermediate point of the length of the 50 pump-barrel, and exteriorly-arranged air-release mechanism connecting the air-reservoir with the projectile-barrel.

2. In an air-rifle of the muzzle-loading type, 55 the combination with the projectile-barrel, of a pump-barrel having its rear portion extended beyond the rear end of the projectile-barrel and bent to form an inclined air-reservoir, a valve at an intermediate point of the barrel, a charging-plunger contained within the 60 barrel in advance of the valve, and exteriorly-arranged air-release mechanism connecting the air-reservoir of the pump-barrel with the projectile-barrel.

3. In a pneumatic rifle of the muzzle-loading type, the combination with the stock, and projectile-barrel, of an air-pump barrel, the rear end of which is extended beyond the rear

end of the projectile-barrel to form an air-reservoir and also a hand-grip which is joined to the stock, a valve at an intermediate point 70 of the barrel, a charging-plunger contained within the pump-barrel in advance of the valve, and air-release mechanism for admitting air from the air-reservoir to the projectile-barrel, said mechanism being arranged 75 exteriorly of the barrels and stock.

4. In a pneumatic rifle of the muzzle-loading type, the combination with the projectile-barrel, of a separate air-pump consisting of a single continuous piece of tubing extending 80 beyond the rear end of the projectile-barrel and having a valved diaphragm intermediate of its ends separating the interior thereof into a pump-cylinder and an air-reservoir, respectively, a charging-plunger contained within 85 the pump-barrel in advance of the valved diaphragm, and exteriorly-arranged air-release mechanism connecting the air-reservoir with the rear end of the projectile-barrel.

5. In a pneumatic rifle of the muzzle-loading type, the main barrel forming both a pump-cylinder and an air-reservoir, and consisting of a single continuous piece of tubing having an integral grip continuation constituting an air-reservoir, a valved diaphragm at an intermediate point of the barrel, a charging-plunger contained within the pump in advance of the valved diaphragm, a separate projectile-barrel, a flexible tube connecting the inner end of the projectile-barrel to the air-reservoir 100 and arranged exteriorly thereof, and a releasing-trigger for the tube.

6. In a pneumatic rifle, a pump-barrel provided with a rear breech extension adjoining the stock and constituting an air-reservoir, a 105 valve-plug interposed between the air-reservoir and the pump-cylinder, a rear sight fitted to the main barrel and having an inner retaining-stem lying in front of the valve-plug, and a separate projectile-barrel having 110 an operative connection with the air-reservoir.

7. In a pneumatic rifle, the combination with the projectile-barrel, of the pump-cylinder barrel having an air-reservoir extension, a 115 valve-plug interposed between the pump-cylinder and the air-reservoir, and a rear sight having an inner retaining-stem extending transversely across the pump-cylinder barrel and lying in front of said valve-plug.

8. In a pneumatic rifle, a pump-barrel having an integral grip extension constituting an air-reservoir and provided with a valve, a separate projectile-barrel adjoining the main barrel and having its bore flared at the rear end, a trigger-guard connecting the two barrels, and exteriorly-arranged trigger-actuated release mechanism disposed within the trigger-guard and including a flexible conveyer connecting the rear end of the projectile-barrel 125 with the air-reservoir, and also forming a holder for the projectile or missile.

9. In a pneumatic rifle, the combination with the projectile-barrel, of a pump-barrel extend-

ed beyond the rear end of the projectile-barrel to form an air-reservoir and consisting of a single continuous piece of tubing having an integral grip continuation constituting an air-reservoir, a valve at an intermediate point of the pump-barrel, a charging-plunger received within the pump-barrel in advance of the valve, a stock closing the rear end of the tube which forms the pump-barrel and reservoir, and an exteriorly-arranged valved air connection between the projectile-barrel and the air-reservoir.

10. In a pneumatic rifle, a pump-barrel, a separate projectile-barrel adjoining the pump-barrel and having its rear end flared or enlarged, and trigger-actuated air-release mechanism including a flexible conveyer connecting the rear end of the projectile-barrel with the pump-barrel and also forming a holder for the projectile.

11. In a pneumatic rifle, a projectile-barrel, a pump-barrel extended in rear of the projectile-barrel to form an air-reservoir, and provided with a valve at an intermediate point, and a pump-piston operable in the pump-barrel, in advance of the valve, in combination with an exteriorly-arranged flexible tube connecting the rear end of the projectile-barrel with the air-reservoir, air-release mechanism, and a trigger-guard connecting the projectile and pump barrels and also forming a guard for the flexible tube. 25

In testimony that I claim the foregoing as my own I have hereto affixed my signature in the presence of two witnesses.

WALTER R. BENJAMIN.
